UNITED STATES PATENT OFFICE

EVERETT WORTHINGTON, OF CHICAGO, ILLINOIS, ASSIGNOR TO THE STROMBERG-CARLSON TELEPHONE MANUFACTURING COMPANY, OF ROCHESTER, NEW YORK, A CORPORATION OF NEW YORK

DESIGN FOR A RADIOCABINET OR THE LIKE

Application filed June 17, 1931. Serial No. 40,237. Term of patent 3½ years.

To all whom it may concern.

Be it known that I, EVERETT WORTHINGTON, a citizen of the United States, residing at Chicago, in the county of Cook and State of Illinois, have invented a new, original, and ornamental Design for Radio Cabinets or the like, of which the following is a specification, reference being had to the accompanying drawings, forming part thereof.

Fig. 1 is a perspective view with the doors closed; Fig 2 is a fragmentary, front view showing the panel when the doors are open; and Fig. 3 is a plan view of a radio cabinet or the like, showing my new design.

I claim:

The ornamental design for a radio cabinet or the like, as shown.

EVERETT WORTHINGTON.
